Specification for Design.

Patented Nov. 12, 1918.

Application filed May 6, 1918. Serial No. 232,946. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Baking-Dish, of which the following is a specification.

In the accompanying drawing I have illustrated a baking-dish constructed in accordance with my invention.

Figure 1 is a side elevation of the dish;

Fig. 2 is an end elevation; and

Fig. 3 is a bottom plan.

The device consists of a dish of transparent material, substantially oval in plan and boat-like in side elevation, having projecting handles 2 at the ends, the top edge rim 3

corresponding to the gun-wale, the upright sides of the dish 4, which are shallow, being ornamented with Doric flutes 5 which shade at the top into the rim 3 and at the bottom into the rounded edge 6. The bottom surface of the dish as shown has radial flutes 7 shading into the curved surface 6 at the edges of the bottom.

Having thus described and illustrated my invention, I claim:

The ornamental design for a baking-dish, substantially as shown and described.

Signed by me at Steubenville, Jefferson county, Ohio, this 2nd day of May, 1918.

JOHN BEISWANGER.
